UNITED STATES PATENT OFFICE

PATRICK LEE HUGGINS, OF DECATUR, GEORGIA, ASSIGNOR OF SIXTY PER CENT TO
S. A. LOVE, OF DE KALB COUNTY, GEORGIA

EMERGENCY COUPLING FOR RAILROAD CARS

Application filed May 18, 1931. Serial No. 538,332.

The present invention relates to improvements in emergency couplings for railroad cars and has for an object to provide certain improvements over my prior Patent No. 5 1,653,433, granted December 30, 1927.

In common with my prior patent, the present improvement has substantially the same objects in view and the aim of the invention generally is to provide a coupling which may 10 perform as a substitute for the usual railway car coupling in the event of breakage or injury to such usual coupling; whereby the cars may be joined together, deferring repairs until the car arrives at the shop.

15 With the foregoing and other objects in view, the invention will be more fully described hereinafter, and will be more particularly pointed out in the claim appended hereto.

20 In the drawing, wherein like symbols refer to like or corresponding parts throughout the several views,

Figure 1 is a side elevation of my improved device as applied to two cars wherein one car 25 has the draw head in position and the other has the draw head torn away.

Figure 2 is a plan view of my improved emergency chain.

Figure 3 is a perspective view showing one 30 method of attaching my emergency chain.

Figure 4 is a view similar to Fig. 1 showing a modification, and

Figure 5 is a detail showing the mode of attachment as applied in Fig. 4.

35 Referring more particularly to the drawing, 10 and 11 designate adjacent railway cars movable over the track 12.

One of the cars 10 is shown as provided with the usual coupling member or draw head 13; while in the other car 11 the draw head is missing, having been injured or torn away. In this event the cars may be coupled together by the use of the improved coupling device which consists of a length of chain 40 peculiarly constructed; such chain being such as to be kept in the cars or in the care of the brakeman.

The improved coupling consists of a central large ring 14 to one side of which is coupled a length of chain 15 terminating in a

smaller ring 16. At its other side the large central ring 14 carries a second length of chain 17 terminating in a turn buckle 18 and a hook 19.

The chain may be of any desired length and the strands or chain sections 15 and 17 may be of the same or different lengths.

Now the improved chain may be applied as shown in Figs. 1 and 4. According to Figs. 1 and 3 the chain section 15 is looped 45 about the transverse beam 20 of the car 11, as shown in Fig. 1, and the terminal small ring or eye 16 may then be passed through the larger central ring 14 and the hook 19 may

be engaged with the small ring 16 after the chain section 17 has been made to encompass the shank or draw-bar of the draw head 13 as indicated in Fig. 1. Of course, the hook 19 may be passed through the central ring 45

14 and the smaller ring 16 remain on the right side thereof; but this central ring 14 carries the inner ends of both chain sections 15 and 17, and moreover acts as a confining element for the free end portions of the chain sections. In this way two companion loops 50

are provided for forming detachable yet effective emergency coupling for the two cars. Also there is uniform distribution of the strain throughout the entire length of the 55 chain.

In accordance with Figs. 4 and 5, the chain section 17 is of short length and the opposite chain section 15 is much longer whereby the small ring 16, after the section 15 is looped 60 about the draw bar 21, may be inserted through the large ring 14 and the chain section 15 drawn through the ring 14 up until the small terminal ring 16 extends partially about the opposite draw bar 22. In this position the small ring 16 is engaged by the hook 19. In Fig. 4 the chain loops are shown 65

as connected to opposite draw bars, one of the draw heads simply being injured, not torn away.

The turn buckle 18 takes up slack in the device or chain. Preferably, the turn buckle is arranged adjacent the hook 19, so that the two may be manipulated together and with facility.

It is obvious that various changes and 70

modifications may be made in the details of construction and design of the above specifically described embodiment of this invention without departing from the spirit thereof, such changes and modifications being restricted only by the scope of the following claim:

In an emergency car coupling, a single length chain having a hook on one end for 10 adjustably engaging the other end portion of the chain and closing the chain into a continuous flexible chain, said continuous chain adapted to be looped at one end upwardly over a draw bar head and behind the same to 15 engage the horn of the head, said continuous chain having the runs crossed beneath the drawbar head, a ring interposed in one run of the chain at a point to lie beneath the coupler and slidably receiving the opposite run 20 of the chain, the other end loop of the chain beyond said ring adapted to be engaged with a portion of an adjacent car and with the hook adjusted to take up general slack in the chain, and a turnbuckle disposed in the chain 25 for drawing the same taut to hold said cars together to permit draft to be transmitted from one car to the other.
